UNITED STATES PATENT OFFICE.

THOMAS JEFFERSON FISHER, OF CARTHAGE, TENNESSEE.

BOOK-CASE.

SPECIFICATION forming part of Letters Patent No. 333,210, dated December 29, 1885.

Application filed May 9, 1884. Serial No. 130,934. (No model.)

To all whom it may concern:

Be it known that I, THOMAS JEFFERSON FISHER, a citizen of the United States, residing at Carthage, in the county of Smith and State of Tennessee, have invented certain new and useful Improvements in Revolving Book-Cases, of which the following is a specification.

The object of my invention is to provide an improved revolving case that can be set upon a table or upon the floor, and having shelves for books, and pigeon-holes for papers, said shelves and pigeon-holes being inclosed by sliding doors; and the invention consists in certain peculiarities of construction, as hereinafter set forth.

In the annexed drawings, Figure 1 is a perspective view of my improved revolving book-case, and Fig. 2 is a sectional elevation of the same on the line $x-x$ of Fig. 1.

Like letters refer to like parts.

A is the pedestal of a shaft, B, by which the book-case is supported, and on which it revolves. This pedestal may be secured by screws $a-a$ to the floor or to a table, desk, or other suitable support. The top C of the book-case, circular in form, is provided on its under side with a socketed cross-frame, D, that is pivotally supported on the upper end 3c of the shaft B. Between the two lower shelves, E E', are secured radial brackets F F, the upper ends of which project inward, and are connected by bolts and nuts to an annular plate, G, that closely surrounds the 35 shaft B. The top C and lower shelves, E E', are connected by vertical brace-rods H H, that pass through the brackets F F, said brace-rods being secured at top and bottom by nuts or other suitable fastenings. The 40 space between the lower shelves, E E', is preferably divided by partitions b b, forming pigeon-holes, that are closed in front by sliding doors K K, which run in grooves or tracks c c, formed near the rims of the shelves. Between the top C and shelf E' are one or more intermediate shelves, L, connected to the top C above and to the shelf below by vertical partitions M M. These shelves E' and L, with their partitions M, form convenient receptacles for 45 books, that may be inclosed, if desired, by means of sliding doors K', running in grooves c' c', and similar to those that inclose the pigeon-holes. The partitions M are preferably arranged at such intervals as to divide 50 the surface of each shelf into four equal parts,

the partitions in each tier being placed midway between those of the adjacent tier or tiers. The sliding doors K K' may be made of a length to extend one-eighth the circumference of the shelves, more or less, and are arranged to lap by each other, so as not to strike or butt together in opening or closing. The rear or inner edges of the circular shelves may also be closed by doors, if desired, or by increasing the width of each shelf, so that it will 65 nearly touch the central support, B, additional room can be obtained in the rear of the books.

In order to provide a means of arranging the books so far apart at the back as to avoid crowding or wedging, and so that they can be readily withdrawn without catching hold of their binding at the top, I provide the shelf with a series of buttons, d d, to prevent the books from coming in close contact with each other, and afford spaces for grasping them at their sides. These buttons or projections d d are simply small knobs or headed pins of wood or metal placed at suitable distances apart in a circle near the edge of the shelf, or 8c in radial lines extending across the shelf. They are placed far enough apart to allow a book to slip easily between them, and are themselves large enough to make a space between the books and keep them apart, so 85 that they can be more easily laid hold of in withdrawing them from the case. There may be only one of these buttons between every two books, or they may be arranged in radial rows, one row of buttons between every two 90 books. In this latter case the buttons are preferably made variable in size, decreased from the outermost to the innermost.

It will be seen that with this form of revolving book-case each book and pigeon-hole can be readily brought within reach, and that there are no projections or outward-opening doors to come in contact with objects upon the table or desk.

Having thus described my invention, what I claim as new, and desire to secure by Letters Patent, is—

In a revolving book-case, a circular shelf provided with buttons d d, adapted to separate the books, substantially as described.

THOMAS JEFFERSON FISHER.
